UNITED STATES PATENT OFFICE.

JACOB B. BLOW, OF PITTSBURGH, PENNSYLVANIA, ASSIGNOR TO BLOW COLLAPSIBLE STEEL CENTERING CO., OF PITTSBURGH, PENNSYLVANIA, A CORPORATION OF NEW JERSEY.

CENTERING.

1,125,943.

Specification of Letters Patent.

Patented Jan. 26, 1915.

Application filed January 3, 1911. Serial No. 600,539.

To all whom it may concern:

Be it known that I, JACOB B. BLOW, a citizen of the United States, residing at Pittsburgh, in the county of Allegheny and State 5 of Pennsylvania, have invented certain new and useful Improvements in Centering, of which the following is a specification.

The invention relates to the centering or forms employed in connection with concrete, 10 and particularly to the box type for the formation of culverts, conduits and the like, and to the wall construction whether employed in a form of the box type or in any other relation. The invention has for its 15 primary objects; the provision of an improved form or mold of the inverted U type; the provision of a mold wherein the walls are made in sections with stiffening means for detachably securing a series of the sections together; the provision of a sectional mold which can be readily changed in dimensions so that the same sections may be used for different sizes of molds to suit conditions; the provision of improved means 20 for securing a plurality of detachable sections of a retaining wall rigidly in assembled position; the provision in a mold of the inverted U type of improved means whereby the mold may be collapsed; the provision in 25 a mold of the inverted U type of improved means for supporting and positioning the top of the mold; and the provision of improved bracing means for the mold. Certain embodiments of the invention are illustrated in the accompanying drawings, wherein:

Figure 1 is a section through a mold or form of the box type embodying the invention, Fig. 2 is a side elevation of the form of 40 Fig. 1, with the lagging broken away to disclose certain of the parts in side elevation and section, Fig. 3 is a perspective view on an enlarged scale of several of the lagging sections employed, Fig. 4 is an enlarged 45 section on the line IV-IV of Fig. 3, Fig. 5 is a section through a modified form of connection, and Fig. 6 is a face view of a retaining wall supplied with the form of connection shown in section in Fig. 5.

As shown in Fig. 1 the mold or form comprises side walls 1 and 2; a top wall 3; ribs 4 for the side walls; ribs 5 for the top wall; 50 wheels 6 for moving the form from place to place; corner braces 8 bolted to the ribs 4 and 5; collapsing turn-buckles 9 and 10; a

connecting member 11 mounted upon the corner braces 8; and jacks 12 mounted upon the connecting member 11 for supporting and positioning the top wall 3.

The side walls 1 and 2 consist of rectangular lagging plates 13 of relatively small size (Fig. 2) and the top wall 3 is similarly composed of plates of the same size and shape as the plates 13. The side walls 1 and 2 are connected to the top wall by means of the sheet metal corner plates 14, which plates serve as a yielding connection whereby the side walls 1 and 2 may be collapsed inwardly. Each of the plates 13 (Fig. 3) has riveted to its side edges the stiffening angles 15 and to its end edges the stiffening angles 16. The end angles on the plates abut as indicated in Fig. 3, and the plates are rigidly secured together and stiffened by means of the rib 4, which rib, in the construction illustrated consists of a member U shaped in cross section, which is secured to the flanges of the angles 16 by means of the bolts 17. These ribs 4 constitute the only means of connection between the plates constituting the side walls 1 and 2. The construction of the top wall 3 is substantially the same as that of the side walls 1 and 2, the ribs 5 being of similar construction and differing only in that the ends are slightly curved as indicated in Fig. 1.

It will be seen that by the use of the sectional construction involving the plates 13 similar in shape and relatively of small size, any desired size of form can be secured, depending upon the number of sections or plate 13 used in building up the sides and top of the form, so that the necessity of carrying in stock the plurality of different sized forms is avoided. Each of the plates 13 is very stiff and rigid because of the angles 15 and 16 used at the edges thereof, and the ribs 4 which cross the joints in the plate serve not only to secure all of the plates together, but also serve to add rigidity to the entire structure. At the same time the structure is such that it may be readily disassembled, and when disassembled may be shipped in very compact form.

The jacks 12 mounted upon the transverse beam 11 serve to maintain the top wall 3 rigidly in position, and also serve to exactly position such wall intermediate its side edges. The bolt and slot connections between the member 11 and the corner 105

braces 8—8 are provided in order to permit the corner braces to move toward each other as the side walls 1 and 2 are collapsed. Prior to collapsing the side walls by means 5 of the turn-buckles 9 and 10, the wedges 19 are knocked out, so that the side walls will have an opportunity to move downward during the collapsing, such downward movement being necessitated because of the 10 stiffening braces 8—8 which tend to force the top wall 3 of the form upward as the side walls are carried inward toward each other. In positioning the mold in the first instance it is brought to its approximately 15 proper size, and the wedges 19 driven into place lifting it to the proper height. The turn-buckles 9 and 10 and the jacks 12 can then be adjusted to exactly position the walls.

20 Another form of connection is illustrated in Figs. 5 and 6, a two piece rib consisting of the plates 20 and 21 being substituted for the rib portion 4 as indicated in Fig. 4. These plates 20 and 21 are secured together by means of the bolts 22, the spacers 25 23 being riveted to the plates 20 and 21 in the manner indicated in Fig. 5. The edges of the plates 20 and 21 are secured to the flanges of the angles 16 by means of the bolts 24. Various other expedients might be obviously adopted in lieu of the two forms of ribs illustrated, the only requirement being that the rib extend across a plurality of plates so as to support the joints 30 between the plates, and that such ribs be secured rigidly but detachably to the flanges of the sections mounted upon the plates 13.

Having thus described my invention and 35 illustrated its use what I claim as new and 40 desire to secure by Letters Patent is the following:—

1. A mold comprising a top wall of sheet metal provided with a transverse stiffening rib, side walls of sheet metal each provided 45 with a vertical stiffening rib and connected with the top wall so that the side walls

may be swung inward, corner braces secured to the said ribs on the top and side walls, a transverse connecting member mounted on the corner braces, and means 50 upon the connecting member for supporting the top wall.

2. A mold comprising a top wall of sheet metal provided with a transverse stiffening rib, side walls of sheet metal each provided 55 with a vertical stiffening rib and connected with the top wall so that the side walls may be swung inward, corner braces secured to the said ribs on the top and side walls, a transverse connecting member mounted on 60 the corner braces, and adjustable supporting means for the top wall mounted on the said connecting member.

3. A mold comprising a top wall of sheet metal provided with a transverse stiffening 65 rib, side walls of sheet metal each provided with a vertical stiffening rib and connected with the top wall so that the side walls may be swung inward, corner braces secured to the said ribs on the top and side 70 walls, a transverse connecting brace having slidably engagement with the corner braces, and adjustable supporting means for the top wall mounted on the said transverse brace.

4. A mold comprising a top wall of sheet metal provided with a transverse stiffening rib, side walls of sheet metal each provided 75 with a vertical stiffening rib and connected with the top wall by a curved sheet metal corner plate, corner braces secured to the said ribs on the top and side walls, a transverse connecting brace between the corner braces, and adjusting means for the top wall mounted on such transverse brace. 80

In testimony whereof I have hereunto signed my name in the presence of the two subscribed witnesses.

JACOB B. BLAW.
